ABSTRACT OF THE DISCLOSURE

Stilbene compounds suitable for the brightening of textiles in combination with cationic softeners, of paper and of weakly acidic substrates. They have the formula

wherein

X and Y independently of one another each represents an optionally substituted phenylamino radical or a radical of the formula

T and Z each represents the radical of the Formula II,
R1 is hydrogen or lower alkyl
R2 is —OH, —CN, —CO—CmH2m+1,

each of R3 and R4 is lower alkyl or lower hydroxy alkyl or together with N a saturated heterocyclic radical, each of R5 and R6 is H or has the meaning of R3 or R4
R7 is lower alkyl bearing optionally —OH, —O—alkyl, —phenoxy, cresoxy or phenyl,
Me is e.g. Na, K, NH4+,
Anion is a colourless anion,
m is 1 to 3,
n is 1 or 2,
p is 2 to 6.

It is generally known that textiles in domestic washing are treated in a rinsing bath following the actual washing operation with agents improving the handle of these textiles. Most of these agents for improving the handling properties (softeners) are cationic compounds.

In this way it is observed that those laundered goods which in the washing operation are brightened with anionic brighteners, such as those which are represented by way of example by bistriazinyl derivatives of 4,4'-diaminostilbene-2,2'-disulphonic acid, suffer by the treatment with cationic softeners a more or less marked reduction in the degree of whiteness. However, this observation is made not only in the said case of household laundry, but every time when an anionic brightener and cationic softener are used simultaneously or in any desired sequence after one another for the treatment of textiles. However, it is not economical to use expensive washing agents containing anionic brighteners of a high quality for household laundry and to destroy by subsequent treat-

2

ment with cationic softeners the brightening effect wholly or partly. Though the brightener itself is not destroyed in this way and is likewise not removed from the fibre, its fluorescence is appreciably weakened or completely obviated by the exchange effect due to the cationic softeners.

It has now been found surprisingly that it is possible to obtain brighteners which, when used in the rinsing bath in very small amount together with the cationic softeners, are able to reinstate to the original value or to an even higher degree the whiteness degree reduced by the treatment with the softener, when there is introduced into the bistriazinyl derivatives of 4,4'-diaminostilbene-2,2'-disulphonic acid 2 to 4 times, for example the residue of a 3-dialkylaminoalkylamine or of a 3-morpholinoalkylamine of which the amino radical contains in the 1-position a substituted alkyl group and, optionally, the resulting products are quaternized. The new brighteners are differentiated from the ones known from Belgian patent specification No. 716,764 by an appreciably better drawing power on cellulose fibres in the cold in combination with cationic softeners.

The invention thus provides novel stilbene compounds of the formula

wherein

X and Y independently of one another each represents an optionally substituted phenylamino radical or a radical of the formula

or of the formula

T and Z each represents the radical of the Formula II or III,

R represents hydrogen or a low molecular weight alkyl radical which may optionally be substituted with hydroxy, alkoxy, cyano, aminocarbonyl, phenyl, phenoxy or cresoxy radicals,

R1 represents hydrogen or a low molecular weight alkyl radical,

R2 represents hydroxy, a cyano, —CO—CmH2m+1,

or —COOR7 radical,

R3 and R4 independently of one another each represents a low molecular alkyl or hydroxyalkyl radical or R3 and R4 together with the nitrogen atom represent a saturated heterocyclic radical,

R5 and R6 independently of one another each represents a hydrogen atom or a low molecular alkyl- or hydroxy-

alkyl radical or R_5 and R_6 together with the nitrogen atom represent a saturated heterocyclic radical, R_7 represents a low molecular alkyl radical which may optionally be substituted with hydroxy, alkoxy, phenoxy, cresoxy or phenyl,

Me represents an equivalent of an alkali or alkaline earth metal or ammonium radical,

Anion represents a colourless anion,

m represents a number from 1 to 3,

n represents 1 or 2

and

p represents a number from 2 to 6,

with the proviso that all radicals

in the substituents T, X, Y and Z may be the same or different from one another and all radicals R_3 to R_6 likewise may be the same or different from one another, and the molecule is devoid of a chromophoric radical and, apart from the two sulphonic acid groups attached to the stilbene residue, contains no other anionic water solubilizing group.

The process for their production is characterized in that there is reacted in any desired sequence 2 mols of a cyanuric halide with

(a) 1 mol of 4,4'-diaminostilbene-2,2'-disulphonic acid or a salt thereof,

(b) 0 to 2 mols of an optionally substituted aminobenzene and

(c) 2 to 4 mols of an amine of the formula

or a mixture of amines of the Formula IV, with the proviso that the amines mentioned at (b) and (c) amount in all to 4 mols, and the reaction product is optionally reacted with an acid or a quaternizing agent, or that there are reacted in any desired sequence 1 mol of a cyanuric halide with

(a) 1 mol of 4-amino-4'-nitro- or -4'-acylaminostilbene-2,2'-disulphonic acid or a salt thereof,

(b) 0 to 1 mol of an optionally substituted aminobenzene and

(c) 1 to 2 mols of amine of the Formula IV or of a mixture of amines of the Formula IV, with the proviso that the amines mentioned at (b) and (c) total 2 mols,

the nitro group is then reduced or the acylamino group hydrolysed and the amino group reacted with 1 mol of a cyanuric halide and the dihalogenotriazinyl compound is reacted in any desired sequence with

(d) 0 to 1 mol of an optionally substituted aminobenzene and

(e) 1 to 2 mols of an amine of the Formula IV or a mixture of amines of the Formula IV, with the proviso that the amines mentioned at (d) and (e) total 2 mols,

and the reaction product is optionally reacted with an acid or a quaternizing agent.

Examples of optionally substituted aminobenzenes are the following: aminobenzene and its derivatives which may contain in the 2-, 3- and/or 4-position low molecular weight alkyl- or alkoxy groups, halogen atoms, cyano groups, alkylsulphonyl groups, optionally mono- or disub-

stituted sulphonic acid amide groups or acylamino groups, for example 2-, 3- or 4-methyl, 2,4-, 2,5-, 2,6- or 3,5-dimethyl-, 2,4,6- or 2,4,5-trimethyl-1-aminobenzene,

4-ethyl-, 4-iso-propyl-, 4-n-propyl-, 4-n-butyl-, 4-tert-butyl-, 4-n-amyl-1-aminobenzene, 2-, 3- or 4-chloro-1-aminobenzene, 2,4- or 2,5-dichloro-1-aminobenzene, 4-fluoro- or 4-bromo-1-aminobenzene, 4-cyano-, 4-methylsulphonyl- or 4-ethylsulphonyl-1-aminobenzene, 3- or 4-aminosulphonyl-, 3- or 4-methylaminosulphonyl-, 3- or 4-ethylaminosulphonyl-, 3- or 4-dimethylaminosulphonyl-, 3- or 4-(2'-hydroxyethylaminosulphonyl)-, 3- or 4-(2'-hydroxypropylaminosulphonyl)-, 3- or 4-di-(2'-hydroxyethyl)-aminosulphonyl- or 3- or 4-morpholinosulphonyl-1-aminobenzene.

Examples of acylamino groups optionally substituted are benzoylamino-, phenylsulphonylamino-, alkylsulphonylamino- and especially the alkanoylamino- and alkoxy carbonylamino groups, for example benzoylamino, 4-methyl- or 4-chlorobenzoylamino, phenyl- and 4-methylphenylsulphonylamino, methyl-, ethyl- and n-propylsulphonylamino, propionylamino, butyrylamino, acetyl-amino, methoxycarbonylamino, ethoxycarbonylamino.

Suitable aminobenzenes with such substituents are, for example, 4-propionylamino-, 4-acetylamino-, 3-acetyl-amino-, 4-methoxycarbonylamino- or 4-ethoxycarbonyl-amino-1-aminobenzene.

The aminobenzenes may also be substituted at the nitrogen atom, for example, as in the following compounds: N-methyl-, N-ethyl- or N-2-hydroxyethylaminobenzene, 3-methyl-1-N-methyl- or -N-ethylaminobenzene.

Aminobenzenes which are preferably used are: aminobenzene, 1-amino-2-, -3- or -4-methyl- or -chlorobenzene, 1-amino-2- or -4-methoxy- or -ethoxybenzene.

The radical A is a low molecular weight alkyl radical which contains the substituent designated as R_2 , for example 2-hydroxyethyl, 2-hydroxypropyl, cyanomethyl, 2-cyanoethyl, 2-cyanopropyl, 2-oxopropyl, 2-oxobutyl, 3-oxobutyl, aminocarbonylmethyl, 2-aminocarbonylethyl, 2-dimethylaminocarbonylethyl, 2-diethylaminocarbonylethyl, 2-morpholinocarbonylethyl, 2-methoxycarbonyl, 2-ethoxycarbonyl, 2-n-butoxycarbonylethyl, 2-(2'-hydroxyethoxycarbonyl)-ethyl, 2-(2'-hydroxypropoxycarbonyl)-ethyl, 2-(3'-hydroxypropoxycarbonyl)-ethyl, 2-(2'-methoxyethoxycarbonyl)-ethyl, 2-(2'-ethoxyethoxycarbonyl)-ethyl, 2-(2'-n-butoxyethoxycarbonyl)-ethyl, 2-benzylloxycarbonylethyl and 2-(2'-phenylethoxycarbonyl)-ethyl.

The radical

of the amine of the Formula IV is exemplified by 2-dimethylamino-, 2-diethylamino-, 2-N-methyl-N-ethyl-amino-, 2-di-n-butylamino-, 2-di-(2'-hydroxyethyl)-amino, 2-N-methyl-N-(2'-hydroxyethyl)-amino-, 2-N-ethyl-N-(2'-hydroxyethyl)-amino-, 2-morpholino- or 2-piperidino-ethylamino, 3-diethylamino-propyl-2-amino, 3-dimethylamino-, 3-diethylamino-, 3-N-methyl-N-ethyl-amino-, 3-N-methyl-N-n-propylamino-, 3-N-ethyl-N-n-butylamino-, 3-di-n-propylamino-, 3-di-n-butylamino-, 3-di-n-pentylamino-, 3-di-(2'-hydroxyethyl)-amino-, 3-N-ethyl-N-(2'-hydroxyethyl)-amino-, 3-morpholino-, 3-pyrrolidino-, 3-piperidino- or 3-hexamethyleneimino-propylamino, 4-dimethylamino-, 4-diethylamino-, 4-N-methyl-N-ethyl-amino-, 4-di-n-butylamino-, 4-N-ethyl-N-(2'-hydroxyethyl)-amino-, 4-di-(2'-hydroxyethyl)-amino- or 4-morpholinobutylamino, 5-diethylamino-, 5-di-n-butylamino- or 5-N-methyl-N-ethylamino-pentylamino, 6-diethylamino-, 6-di-n-butylamino- or 6-N-methyl-N-ethylamino-hexylamino.

Preferred amines of the Formula IV are, for example, N-(3-dimethylaminopropyl)-, N-(3-diethylaminopropyl)-, N-(3-di-n-butylaminopropyl)-, N-(3-morpholinopropyl)-,

5

N-(3-piperidino-propyl)-, N-(3-N'-ethyl-N'-methylamino-propyl)-N-aminocarbonylmethyl-amine, -N-(2'-cyanoethyl)-amine, -N-(2'-aminocarbonylethyl)-amine, -N-(2'-dimethylaminocarbonylethyl)-amine, -N-(2'-diethylaminocarbonylethyl)-amine, -N-(2'-morpholinocarbonylethyl)-amine, -N-(2'-ethoxycarbonylethyl)-amine, -N-(2'-methoxycarbonylethyl)-amine, -N-(2' - hydroxyethoxycarbonylethyl)-amine, -N-(2'-methoxyethoxycarbonylethyl)-amine, -N-(2'-methylcarbonylethyl)-amine, N-[3-di-(2'-hydroxyethyl)-aminopropyl - N - (2"-cyanoethyl)-amine, -N-(2"-aminocarbonylethyl) - amine, -N-(2"-dimethylaminocarbonylethyl) - amine, -N-(2" - diethylaminocarbonylethyl) - amine, -N-(2"-morpholinocarbonylethyl)-amine, -N-(2"-ethoxycarbonylethyl)-amine, -N-(2"-hydroxyethoxycarbonylethyl) - amine, -N-(2"-methoxyethoxycarbonylethyl)-amine, -N-(2"-methylcarbonylethyl)-amine.

The amines of the Formula IV required as intermediate products may be obtained, for example, by the reaction of amines of the formula

with acrylonitrile, optionally substituted acrylic acid alkyl esters and acrylic acid amides or with the corresponding methacrylic acid derivatives, with alkylene oxides (especially ethylene- and propylene oxide) or with vinyl-alkyl ketones (vinyl-methyl ketone), at temperatures of from 0-100° C. (20-60°).

Suitable quaternizing agents are for example, esters of sulphuric acid, e.g. dimethylsulphate or diethylsulphate, or the esters of aromatic or aliphatic sulphonate acids, e.g. benzene-, 4-methylbenzene- or 4-chlorobenzenesulphonic acid methyl ester, -ethyl ester or n-butyl ester, methane-, ethane-, 1-propane- or 2-propanesulphonic acid methyl ester or -ethyl ester. As alkylating agents there are suitable also alkyl- and aralkylhalides, e.g. methylchloride, methylbromide, ethylbromide, n-butylbromide, benzylchloride and benzylbromide. Furthermore, there may be used as alkylating agent alkylhalides with from 1 to 5 carbon atoms which are substituted with hydroxyl, alkoxy, phenoxy, cresoxy, cyano or preferably with aminocarbonyl groups, e.g. 2-chloro- or 2-bromoethanol, 2-methoxy-, 2-ethoxy-, 2-n-butoxy-, 2-phenoxy- or 2-paracresoxyethyl chloride or bromide, chloroacetonitrile and preferably chloro- or bromoacetic acid amide or β -chloropropionic acid amide.

The reaction with cyanuric halides, e.g. cyanuric bromide and especially cyanuric chloride, with the 4,4'-diaminostilbene-2,2'-disulphonic acid or with a water soluble salt thereof is effected with aqueous medium when the cyanuric halide is merely suspended in water, or in aqueous-organic medium when the cyanuric halide is first dissolved in an organic solvent (benzene, toluene, chlorobenzene, acetone) and the solution is added dropwise to an aqueous solution of the 4,4'-diaminostilbene-2,2'-disulphonic acid. The addition of a dispersing agent may increase the reaction velocity.

The replacement of the first halogen atom of the cy-anuric halide is carried out at temperatures of from 0° to 10° C. and pH values of from 3 to 7. The replacement of the second halogen atom [introduction of an optionally substituted phenylamino residue or of a residue of the Formula II] is suitably effected in the temperature range of from 20° to 60° C. and at a weakly acid to weakly alkaline reaction, for example at pH values of from 4 to 8, while for the replacement of the third halogen atom [introduction of a residue of the Formula II] the temperature is advantageously kept to 80° to 100° C. and the pH value between 4 and 10. 60 65 70

The hydrogen halide liberated during the reaction is neutralized with alkalis, for example an alkali metal hydroxide or carbonate, or tertiary organic amines, e.g. triethanolamine.

6

The isolation of the unquaternized brightener produced according to the invention may be effected by salting out, acidifying or evaporating the reaction solution, whereby pulverulent products result. However, it is likewise possible, after separating the salts, to produce liquid products with the addition of a solubilizing agent, such as for example a polyvalent alcohol [ethylene- or propylene glycol, di- or tri-ethylene glycol, polyethylene glycol, di- or tri-propylene glycol, 1,3-dihydroxypropane, 1,4-dihydroxybutane, 2,3-dihydroxybutane, 2-methyl - 2,4 - dihydroxypentane, glycerine, hexanetriol, bis-(2'-hydroxyethyl)-sulphide], ether alcohol [2-methoxy-, 2-ethoxy- or 2-n-butoxy-ethanol, 2-(2'-ethoxy-ethoxy)-ethanol, 2-(2'-n-butoxyethoxy)-ethanol], a sulphoxide or sulphone (dimethylsulphoxide, di-ethylsulphoxide, tetramethylene sulphone), an amide [formamide, dimethylformamide, diethylformamide, dimethylacetamide, diethylacetamide, phosphoric acid-tris-(dimethylamide), urea] or an alkanolamine (mono-, di- or tri-ethanolamine or -propanolamine).

The quaternization may be effected in aqueous, aqueous-organic or organic suspension or solution at temperatures of from 0° to 100° C. and pH values of from 4 to 8, preferably at 20-60° C. and in the pH range of from 6 to 8. All tertiary amino groups or only some of them may be quaternized, at least 1 mol of the quaternizing agent being used for each tertiary amino group to be quaternized. When using a volatile quaternization agent, e.g. methylchloride, methylbromide, ethylbromide, it is suitable to work in a pressurized vessel. Any excess of quaternizing agent is destroyed by the addition of sodium hydroxide solution and stirring the mixture at about 60° C. until the pH value no longer changes. The above mentioned polyvalent alcohols, ether alcohols, sulphoxides, sulphones and amides or their mixtures with water are suitable reaction media for the quaternization

water are suitable reaction media for the quaternization. In order to obtain the compounds of the Formula I in which R [Formula III] represents hydrogen, the compounds with tertiary amino groups are stirred in water or a mixture of water and a solvent mentioned for the quaternization of 1 mol of acid is added for each tertiary amino group to be protonized. Working is advantageously effected at 0° to 100° C., preferably at 20° to 80° C., in such a way that all tertiary amino groups present are protonized and the pH value of the solution or suspension is adjusted to about 3 to 5. As acids there may be used strong inorganic acids, e.g. hydrogen chloride or hydrogen bromide; however, organic acids, e.g. formic acid, acetic acid, propionic acid or oxalic acids, are likewise suitable.

The isolation of the protonized or quaternized compounds may be effected in the above described manner. Valuable brighteners correspond to the formula

wherein
X₁ and Y₁ independently of one another each represents
a phenylamino- or methylphenylamino radical or a
radical of the formula

OR

T_1 and Z_1 each represents a radical of the Formula VII or of the Formula VIII

and

Me, R, R₂, R₃ and R₄ have the above significance.

Particularly valuable brighteners are those of Formula VI, wherein R_2 [in the Formulae VII and VIII] represents an optionally mono- or disubstituted aminocarbonyl radical.

The new brighteners produced according to the invention are suitable in the non-quaternized form and especially in the quaternized form for the brightening of textiles in combination with cationic softeners which may optionally also contain antistatically effective agents. Thanks to their excellent drawing ability on to cellulose fibres in the cold in the presence of cationic softeners they are especially suitable for use in "soft rinsing agents" which have been used in households for some time.

The quantities of brightener to be used amounts to 1-10% preferably 3-6%, based on 100% softener.

The brighteners of the invention afford the possibility to industry to combine simply and economically brightening and improvement of handle. Furthermore, they improve the appearance of weakly acid substrates, preferably of inorganic nature, e.g. silica, clay, kaolin etc., which is of especial importance in the paper industry.

A likewise very good brightening effect is shown by the brighteners according to the invention when used as coating compositions for papers.

Those of the brighteners according to the invention which contain 4 quaternized amino groups may likewise be applied to cellulose fibres from strongly acid medium, for example at pH values of from 1 to 2, and show good brightening effects. They may be used together with auxiliaries for crease-proofing cellulose fibres, for example with resins such as dimethylolethylene urea, dimethylolpropylene urea, dimethylol-4,5-dihydroxyethylene urea, dimethylolmonoalkyl-carbamate and others. The condensation of synthetic resins is effected in a pH value range of from 1 to 2 which is usual in moist or wet cross-linking.

In the following examples parts and percentages are by weight and temperatures are stated in degrees centigrade.

EXAMPLE 1

A solution of 190 parts cyanuric chloride in 635 parts acetone is run into 2000 parts of ice water during 10 minutes. A solution of 185 parts of 4,4'-diaminostilbene-2,2'-disulphonic acid and 106 parts of anhydrous sodium carbonate in 1500 parts of water is then added dropwise at 0 to 5° while stirring during one hour into the resulting suspension. In this way a suspension results which contains 355 parts of the sodium salt of 4,4'-bis-(2",4"-dichloro-1",3",5"-triazinyl-6"-amino) - stilbene - 2,2'-disulphonic acid. After the diazo reaction no longer shows primary, aromatic amino groups, 93 parts of aminobenzene are added to this suspension, the mixture is heated to 40° for one hour while gradually adding 400 parts of 10% sodium hydroxide solution, 201 parts of β -(3'-diethylaminopropylamino)-propionic acid amide are added, and, after distilling off the acetone, the mixture is heated for 5 hours to 95-100° while gradually adding a further 400 parts of 10% sodium hydroxide solution. The product which separates out in the warmth as a viscous mass, becomes solid and brittle on cooling. After separating off the mother liquor, the product is comminuted, stirred with 1500 parts of cold water, suctioned off and dried in a vacuum. It is highly suitable for brightening textiles of

all kinds, especially those from cotton in the cold in the presence of cationic softeners such as for example di-stearyldimethylammonium chloride.

The resulting brightener corresponds to the formula

The required propionic acid amide is produced by adding 71 parts of acrylic amide to 130 parts of 3-diethylaminopropylamine at 40° and continuing stirring for one hour at this temperature.

EXAMPLE 2

To the suspension, obtained according to Example 1 of 355 parts of the sodium salt of 4,4'-bis-(2",4"-dichloro-1",3",5"-triazinyl - 6" - amino) - stilbene-2,2'-disulphonic acid in 2000 parts of water and 635 parts of acetone there is added, while stirring, at 12° during about 10 minutes 201 parts of β -(3'-diethylaminopropylamino) - propionic acid amide, the mixture is heated, while gradually adding 400 parts of 10% sodium hydroxide solution, to about 40° and stirring for one hour at this temperature is effected, a further 201 parts of the same propionic acid amide are added and the mixture, after distilling off the acetone, is heated for 6 hours to 95-100° while gradually adding 400 parts of 10% sodium hydroxide solution. The product is separated out in the warmth in the form of a viscous mass and is completely separated by the addition of sodium chloride (150 g./litre). The brightener is suctioned off, washed with dilute sodium chloride solution and dried. It constitutes a light yellow powder which is very effective, in combination with cationic softeners, for brightening cotton and alone for brightening weakly acid substrates, e.g. silica, clay or kaolin.

The brightener produced as above corresponds to the formula

An equally effective brightener is obtained when in this example the β -(3'-diethylaminopropylamino) - propionic acid amide is replaced once or twice each with 233 parts 60 of β -[3'-di(2' - hydroxyethyl) - aminopropylamino]-propionic acid amide or each with 257 parts of β -[3'-di(n-butyl)-aminopropylamino]-propionic acid amide, the procedure being otherwise the same. These amines are produced, for example, by the reaction of 3-[di-(2'-hydroxyethyl)-amino]-propylamine or of 3-di-n-butylaminopropylamine with acrylic acid amide in the manner described in Example 1.

EXAMPLE 3

70 To the suspension, obtained according to Example 1, of the sodium salt of 355 parts of 4,4'-bis-(2",4"-dichloro-1",3",5"-triazinyl - 6" - amino)-stilbene-2,2'-disulphonic acid in a mixture of acetone and water there is added, while stirring at 12°, first 46.5 parts of amino-
 75 benzene and the temperature is allowed to rise slowly

while simultaneously adding dropwise 10% sodium hydroxide solution. After about 15 minutes the diazo reaction no longer shows the presence of aminobenzene. While simultaneously introducing dropwise sodium hydroxide solution, 53.5 parts of 1-amino-2-methylbenzene are added subsequently. In all 400 parts of 10% sodium hydroxide solution are added dropwise and the temperature at the end has been increased to 40°. At this temperature the mixture is stirred for one more hour and then 201 parts of β -(3'-diethylaminopropylamino)-propionic acid amide are added. The resulting mixture is heated for 4 hours to 95-100° while slowly adding 400 parts of 10% sodium hydroxide solution. The product is completely separated by the addition of sodium chloride (100 g./litre), after cooling it is comminuted, filtered off and washed with 10% sodium chloride solution and dried in a vacuum.

The resulting product contains as active component a compound of the formula

(XI)

in addition to small quantities of the symmetric compounds containing two phenylamino residues or two 2-methylphenylamino residues and is as effective as the symmetrically substituted brightener described in Example 1.

EXAMPLE 4

To the suspension, produced as in Example 1, of 355 parts of intermediate product from cyanuric halide and 4,4'-diaminostilbene-2,2'-disulphonic acid in a mixture of acetone and water there are added first, while stirring at 10-12°, 46.5 parts of aminobenzene and then 53.5 parts of 1-amino-2-methylbenzene, the procedure being as in Example 3. After the presence of the aromatic primary amines is no longer detectable, 215 parts of β -(3'-morpholinopropylamino)-propionic acid amide are added at 40° to the suspension and the mixture is heated for 5 hours to 95-100° while simultaneously adding dropwise 400 parts of 10% sodium hydroxide solution. The product is completely separated off by salting out (100 g. of sodium chloride/litre) and worked up in the usual way.

The brightener present in the form of a yellow powder contains mainly the compound of the formula

(XII)

in addition to small amounts of the symmetrical compounds having two phenylamino or two 2-methylphenylamino residues.

It is equally suitable for combination with cationic sorters as are the products described in Examples 1 to 3.

When the aminobenzene and the 1-amino-2-methylbenzene used in this example are together replaced with 215 parts of β -(3'-morpholinopropylamino)-propionic acid amide, a product results which is very similar in effect to compound first mentioned in Example 2.

EXAMPLE 5

A solution of 19 parts of cyanuric chloride in 100 parts of acetone is run into 200 parts of a mixture consisting of equal parts of ice and water. A solution, neutralized with sodium hydroxide, of 40 parts of 4-nitro-4'-aminostilbene-2,2'-disulphonic acid in 400 parts of water is added drop-

wise during 10 minutes at 0-5° while stirring to the resulting suspension. During the course of one hour a solution of 5.5 parts of sodium carbonate in 50 parts of water is added dropwise in such a way that the reaction product is always weakly acid to neutral (pH value 6 to 7). To the mixture which has been neutralized and freed from starting material, there are then added 9.3 parts of aminobenzene, the temperature is raised during about one hour to 35° and stirring is continued at this temperature until aminobenzene can no longer be detected with the diazo test, which occurs after 1-2 hours. The resulting hydrochloric acid is neutralized by the gradual addition of a solution of 5.5 parts of sodium carbonate in 50 parts of water. 20.1 parts of β -(3'-diethylaminopropylamino)-propionic acid amide are then added to the reaction mixture, the temperature is raised to 85° and stirring for about 4 hours is continued at this temperature, whereby the resulting hydrochloric acid is continuously neutralized with

sodium carbonate. The resulting condensation product of the formula

(XIII)

11

is separated after cooling by the addition of sodium chloride, filtered off and washed with 10% sodium chloride solution.

The product, after it has been washed neutral, is then added during the course of one hour at 90-100° in a mixture consisting of 500 parts of water, 66 parts of iron filings and 15 parts of glacial acetic acid. As soon as nitro compound has disappeared, the solution is made alkaline with sodium carbonate, filtered and the resulting solution of the disodium salt of 4-amino-4'-[2"-phenylamino-4"-4"-N-(2"-aminocarbonyl-ethyl)-N-(3"-diethylamino-propyl)-amino-1",3",5"-triazinyl-6"-amino]-stilbene-2,2'-disulphonic acid has its pH value adjusted to 7 by adding dilute hydrochloric acid. This solution is added dropwise during 10 minutes at 0-10° to a suspension which has been obtained by mixing 19 parts of cyanuric chloride, dissolved in 100 parts of acetone, with 100 parts of ice and 100 parts of water. The resulting hydrochloric acid is again neutralized by gradually adding a solution of 5.5 parts of sodium carbonate in 50 parts of water. When the condensation is complete, 10.7 parts of 1-amino-2-methylbenzene are added, the temperature is raised during one hour to 30° and stirring at this temperature is continued for 4 hours, whereby the resulting hydrochloric acid is neutralized by gradually adding sodium carbonate solution. 20.1 parts of β -(3"-diethylaminopropylamino)-propionic acid amides are then added to the reaction mixture, the temperature is raised to 85° and stirring at this temperature for 4 hours is effected, while simultaneously neutralizing the resulting hydrochloric acid with sodium

12

This stilbene compound is slightly more effective than the non-quaternized compound of the Formula IX for brightening cotton in combination with cationic softeners.

Instead of dimethylsulphate it is possible to use 15.4 parts of diethylsulphate or 18.6 parts of 4-methylbenzenesulphonic acid methyl ester for effecting quaternization. When benzylchloride is used as quaternization agent (12.65 parts), advantageously working is effected at room temperature (about 24 hours).

EXAMPLE 7

Working is effected in the manner described in Example 6 while using 68.4 parts ($\frac{1}{20}$ mol) of the compound of the Formula X or 79.5 parts ($\frac{1}{20}$ mol) of the compound bearing di-(n-butyl)-amino groups instead of the di-ethylamino groups (last paragraph of Example 2) and 25.2 parts of dimethylsulphate and quadruple quaternized compounds result.

EXAMPLE 8

57.6 parts ($\frac{1}{20}$ mol) of the compound of Formula IX are stirred at room temperature in 550 parts of dimethylformamide and dissolution is effected by the addition of 30 parts of water. During about 15 minutes 8.2 parts of 85% formic acid are added dropwise to this solution, whereby the pH value drops to 4 to 5. A stable solution of the protonized brightener results.

EXAMPLE 9

74.8 parts ($\frac{1}{20}$ mol) of the brightener of the formula

carbonate as already described. After the addition of sodium chloride, cooling to room temperature is effected. This product separates out in the warmth as a viscous mass which solidifies on cooling. It is then pulverized, washed with sodium chloride solution and dried in a vacuum. A yellowish powder results which is practically insoluble in water, but is easily soluble in dimethylformamide or dimethylsulphoxide. It corresponds to the Formula XI. The product is effective as a brightener in manner similar to the product obtained according to Example 3.

EXAMPLE 6

57.6 parts of ($\frac{1}{20}$ mol) of the compound of the Formula IX are stirred into 547 parts of dimethylformamide at room temperature and a clear solution is produced by adding 29 parts of water. During about 30 minutes 12.6 parts of dimethylsulphate are added dropwise to this solution, stirring is then effected for 2 hours at room temperature and during one hours at 60°. Any small excess of dimethylsulphate is destroyed by the addition of sodium hydroxide solution while stirring at 60°. The reaction solution contains, in addition to small amounts of unquaternized compound of the Formula IX, the compound of the formula

(produced according to the last paragraph of Example 2) are dissolved at 60-70° in 330 parts of dimethylformamide and 330 parts of water while stirring. About 24 parts of 30% hydrochloric acid are then added so as to adjust the pH value to about 3 to 4, and a stable solution results of the protonized brightener in the form of the hydrochloride.

By replacing the brightener of Formula XV by the other brightener described in the last paragraph of Example 2 which contains di-(n-butyl)-amino groups instead of di-(β -hydroxyethyl)-amino groups, a similarly protonized brightener is produced.

The following Table 1 contains further symmetric stilbene compounds of the Formula I which are produced according to the details in Examples 1 and 2 and 60 are characterized by the symbols T, X, Y, Z and Me.

¹ Formula XV. ² Last paragraph.

17
EXAMPLE OF USE A

Production of a softening preparation: 3 parts of the solution, obtained according to the details of Example 6, of the compound of Formula XIV are added to 10 parts of a softener paste containing 75% of distearyltrimethylammonium chloride and 25% of isopropanol. Stirring is effected and slow dilution with water under constant stirring until the content of softener is 5%.

20 parts of bleached cotton material in 800 parts of water containing 8 parts of the above softener preparation are treated for 15 minutes at 20°. The material is centrifuged without rinsing and subsequently ironed until dry. The resulting material has a soft handle and appears much whiter than a sample treated in the softener bath without any brightener for purposes of comparison.

Instead of distearyltrimethylammonium chloride it is possible to likewise use other cationic compounds, for example on a basis of 1-methyl-1-alkanoylaminoethyl-2-alkylimidazoliniummethylsulphate or a condensation product of stearic acid and N-β-hydroxyethylmethylenediamine in the form of a salt.

EXAMPLE OF USE B

A liquor is produced containing 0.5 g. of softener per litre using a softener composition composed of the following constituents

Triethanolamine	-----	g	5
Dimethylformamide	-----	g	10
Distearyltrimethylammonium chloride	-----	g	4
Brightener according to Example 1	-----	mg	160

Bleached cotton material (cretonne) is treated in the cold for 15 minutes at a liquor ratio of 1:140; centrifuging without rinsing is effected and subsequently wringing until dry (Sample A). When in the above softener composition the brightener according to the invention is replaced with the one described in Example 1 of Belgian patent specification No. 716,764, the procedure being otherwise the same, a material results which fluoresces markedly less (Sample B), as evidenced by the values given by a fluorimeter

18
(measured in an apparatus "Modell Schiltknecht," Zurich) but is likewise clearly ascertainable by the naked eye.

Scale degrees	80.5
5	Sample A (brightener of the invention) -----
	Sample B ----- 69

EXAMPLE OF USE C

Bleached cotton cretonne is treated in a bath [5 g./litre of a washing agent based on a basis of sodium dodecylbenzenesulphonate and 2% of anionic brightener (a triazinyl derivative of 4,4'-diaminostilbene-2,2'-disulphonic acid) based on the washing agent] at a liquor ratio 1:40 during 30 minutes at 95° and rinsing is subsequently effected as in the normal washing operation. To 10 part of the washed cotton material (A) there is added in the last rinsing bath as much of a softener preparation in accordance with Example of Use A, which preparation contains 4% of the brightener described in Example 1 (based on 100% softener), so that the rinsing liquor contains 0.5 g. of softener per litre. Treatment in the cold is effected for 15 minutes (liquor ratio 1:40), centrifuging is effected and ironing.

15 The other part of the washed cotton material (B) is treated for purposes of comparison in similar manner in a rinsing bath containing softening agent, but without the addition of the brightener according to the invention. The Samples A and B are compared in daylight. Whereas Sample B appears clearly more yellow than before the treatment with the softener, the Sample A appears clearly brighter than the Sample B and also brighter than material which has not been treated in a rinsing bath containing softener.

20 From the foregoing it is seen that the brightener in accordance with the invention combined with cationic softeners is capable of increasing the whiteness degree of cotton material despite the already present anionic brightener, a result which was in no way to be expected.

25 Formulae of representative stilbene compounds of the foregoing examples are as follows:

Example 2 (last paragraph)

Example 2 (last paragraph)

Example 7 (first compound)

19

Example 7 (second compound)

20

Example 8

Example 9 (last paragraph)

Example 136

Example 150

Example 174

21
Example 178

22

Example 196

Having thus disclosed the invention what we claim is:

1. A stilbene compound of the formula

wherein

X and Y independently of one another each represents an unsubstituted or substituted phenylamino radical in which the ring substituents may be lower alkyl, lower alkoxy, halogen, cyano, alkylsulphonyl, aminosulphonyl, or acylamino and the N- substituents may be lower alkyl or lower hydroxyalkyl; or a radical of the formula

30 R_5 and R_6 independently of one another each represents a hydrogen atom or a low molecular alkyl- or hydroxy-alkyl radical or R_5 and R_6 together with the nitrogen atom represent piperidino, morpholino, pyrrolidino, or hexamethylene imino,

35 R_7 represents a low molecular alkyl radical which may optionally be substituted with hydroxy, alkoxy, phenoxy, cresoxy, or phenyl,

35 Me represents an alkali metal, ammonium, or an equivalent of an alkaline earth metal,
Anion represents a colourless anion,
 m represents a number from 1 to 3, and
 n represents 1 or 2

40 with the proviso that
all radicals

or of the formula

T and Z each represents the radical of the Formula II or III,

R represents hydrogen or a low molecular weight alkyl radical which may optionally be substituted with hydroxy, alkoxy, cyano, aminocarbonyl, phenyl, phenoxy or cresoxy radicals,

R1 represents hydrogen or a low molecular weight alkyl radical,

R2 represents hydroxy, a cyano, $-\text{CO}-\text{C}_m\text{H}_{2m+1}$,

R3 and R4 independently of one another each represents a low molecular alkyl or hydroxyalkyl radical or R3 and R4 together with the nitrogen atom represent piperidino, morpholino, pyrrolidino, or hexamethylene imino,

50 in the substituents T, X, Y, and Z may be the same or different from one another and all radicals R_3 to R_6 likewise may be the same or different from one another, and the molecule is devoid of a chromophoric radical and, apart from the two sulphonate groups attached to the stilbene residue, contains no other anionic water solubilizing group.

55 2. A stilbene compound according to claim 1 wherein X and Y independently of one another each represents a phenylamino- or methylphenylamino radical or a radical of the formula

or

and T and Z each represents a radical of the Formula VII or of the Formula VIII.

70 3. A stilbene compound according to claim 2 wherein

4. The stilbene compound according to claim 1 of the formula

5. The stilbene compound according to claim 1 of the formula

6. The stilbene compound according to claim 1 of the formula

8. The stilbene compound according to claim 1 of the formula

7. The stilbene compound according to claim 1 of the formula

9. The stilbene compound according to claim 1 of the formula

10. The stilbene compound according to claim 1 of the formula

23

11. The stilbene compound according to claim 1 of the formula

12. The stilbene compound according to claim 1 of the formula

13. The stilbene compound according to claim 1 of the formula

14. The stilbene compound according to claim 1 of the formula

15. The stilbene compound according to claim 1 of the formula

16. The stilbene compound according to claim 1 of the formula

17. The stilbene compound according to claim 1 of the formula
